WATER CRAFT

Shely W. McGuire, 2355 Olivia Ave., Yuma, Ariz.

Filed Oct. 27, 1964, Ser. No. 82,342

Term of patent 14 years

(Cl. D71—1)

FIG. 1

FIG. 2

FIG. 3

FIG. 4

FIG. 5

FIG. 1 is a top plan view of a water craft showing my new design;

The dominant features of my design reside in the portions shown in full lines.

I claim:

The ornamental design for a water craft, as shown and described.
